(57) CLAIM

The ornamental design for a case for cigarette paper with paper, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is an external side perspective view of a case for cigarette paper with paper showing our new design; and FIG. 1.2 is an inner side perspective view thereof.

1 Claim, 2 Drawing Sheets
(2 of 2 Drawing Sheet(s) Filed in Color)
